ROTATABLE RUBBER HEEL

Benjamin Gilowitz, Bronx, N. Y., assignor of twelve and one-half per cent to Irving Skrilow, and twelve and one-half per cent to Abraham Levin, both of New York, N. Y.

Application May 7, 1947, Serial No. 746,465

1 Claim. (Cl. 36—35)

1

My invention aims to provide a new and improved shoe heel of rubber or other suitable composition, embodying a rotatively adjustable rear section which may be turned successively to different positions as it becomes worn, and may be finally discarded and replaced with a new section at trivial cost.

In carrying out the above end, a further object is to provide a heel body carrying the rotatively adjustable section and so constructed that it may be trimmed and sanded to fit a leather heel to which it is attached, without danger of the trimming and sanding tools disturbing the desired relation of the rotatively adjustable section with the rear edge of said body.

Another object is to provide a novel construction in which the rotatively adjustable section may be secured both by a central screw and by cement, the construction, however, being such as to leave un-cemented areas which facilitate insertion of a screw driver or the like to pry the rotatively adjustable section off after removal of said screw, whenever said section is to be adjusted to another position or is to be discarded in favor of a new one.

The rotatively adjustable heel section is formed with a central socket in which the head of the attaching screw is confined, and a plug is provided for this socket to prevent dirt from packing therein; and another object is to make novel provision to facilitate removal of this plug, when access to the screw is required.

Yet another object is to provide a construction which may be expeditiously manufactured, and profitably sold at a reasonable price.

Figure 1 of the accompanying drawings is a side elevation showing one form of the invention, the improved heel being applied to a leather heel in readiness for trimming and sanding to accurately fit the latter.

Fig. 2 is a bottom plan view of the improved heel applied to the shoe.

Fig. 3 is a view similar to Fig. 2, the rotatively adjustable heel section being removed.

Fig. 4 is an enlarged central vertical sectional view as indicated by line 4—4 of Fig. 2.

Fig. 5 is a front end view of the heel prior to application.

Fig. 6 is a top plan view of the rotatively adjustable heel section.

Fig. 7 is an edge view of the heel section shown in Fig. 6.

Fig. 8 is a side elevation of the removable plug which normally occupies the socket in which the head of the attaching screw is accessible.

2

Fig. 9 is a view similar to Fig. 1 showing a different form of construction.

Figs. 10 and 11 are views similar to Figs. 2 and 3, showing the construction of Fig. 9.

Fig. 12 is an enlarged longitudinal section as indicated by line 12—12 of Fig. 10.

Fig. 13 is a front end view of the heel of Figs. 9 to 12, before application.

Fig. 14 is a top plan view of the rotatively adjustable heel section of Figs. 9 to 13.

Fig. 15 is an edge view of the heel section of Fig. 14.

Preferences have been disclosed in the drawings above briefly described, and while they will be rather specifically explained, it is to be understood that minor variations may be made within the scope of the invention as claimed.

In the form of construction illustrated in Figs. 1 to 8, a heel body 16 is provided, said body having a front edge 17, longitudinal edges 18, and a rear edge 19, the latter being curved on an arc of a circle. The front corner portions of the body 16 are provided with downwardly projecting tread lugs 20 which may be integral with said body, as shown, or may be detachable to be replaced when worn. Behind these lugs 20, the body 16 is formed with a polysided opening 21 from its lower to its upper side. This opening is shown of square form and its center is concentric with the arc of the rear edge 19. Suitable nail holes 22 are provided through the body 16 to receive nails 23 for securing said body to a conventional leather heel 24, and the upper portion of this body is formed with an integral rib 25 to be trimmed and sanded when the rubber heel is applied to said leather heel. This rib is flush with the upper side of the body 16, extends along the edges 19 and 18 and terminates at the front edge 17, said rib being widely spaced above the bottom of said body 16. When applying the improved heel to a leather heel, one of the former is preferably selected of such size that its rib 25 will not project beyond the leather heel. The latter and the rib 25 may then be trimmed and sanded without danger of the trimming and sanding tools touching any of the edges 18 and 19 or the circular rotatable heel section 26 hereinafter described, and changing the shape thereof.

A rotatable heel section 26, of circular outline, contacts with the lower side of the body 16, and the peripheral edge 27 of said heel section 26, is flush with the rear edge 19 of the body 16. Both this rotatively adjustable heel section 26 and the body 16 are of concavo-convex form before application of the heel to a shoe, as will be clear

from Figs. 5 and 7, to insure tighter contact at the edges when drawn into flat form. The upper side of the section 26 is provided with an integral boss 28 shaped for snug reception in the opening 21 of the body 16, said boss being of a height to contact with the lower side of the leather heel 24, as seen in Fig. 4. The section 26 is formed with a central socket 29 which opens through the lower side of said section, and is formed also with a central opening 30 which extends from said socket 29 to the upper side of the boss 28. An attaching screw 31 extends through the opening 30 and is of a length to be threaded tightly into the leather heel 24 as seen in Fig. 4.

In addition to securing the rotatively adjustable heel section 26 by means of the screw 31, it is preferably cemented also to the body 16. The upper side of section 26, however, is provided with a plurality of radial surfaces 32 which are so smooth that the rubber cement or other cement used, will not adhere to them. Such smooth areas 32 are obtained by highly polishing the portions of the mold which form them. The intervening areas 33 are made quite rough and are preferably raised somewhat from the surfaces 32, providing shallow grooves 34 in the heel section 26. These grooves permit the insertion of a screw driver or the like between the section 26 and the body 16 to pry said section off after removal of the screw 31, when said section is to be turned to another position after wear, or is to be thrown away and replaced with a new section. The rubber cement will adhere to rough areas 33 and to the lower side of the body 16 which does not have the very smooth or polished surface of the areas 32, and hence the cement will effectively hold the edges of parts 16 and 26 together.

A plug 35 normally fills the socket 29 below the head of the screw 31 and prevents dirt from accumulating in said socket. This plug is formed with a small central bore 36, and one or more pull cords 37 is/are anchored to said plug at the upper end of said bore, as seen at 38 in Fig. 4. In the present disclosure, there are two of these pull cords formed from a single thread folded upon itself as shown at 39. Normally, these pull cords are crammed tightly into the bore 36 as indicated in Fig. 4, although the cramping is accomplished much more tightly than shown in said view. When the plug 35 is to be removed, the pull cords are picked from the lower end of the bore 36 and are then pulled outwardly as seen in Fig. 8, in which position, they may be readily used to extract said plug 35 from the socket 29. The plug is molded from rubber or the like and has anti-slipping fabric molded therein as indicated at 40.

Preferably the body 16, the rotatively adjustable heel section 26, and the plug 35, are all formed from rubber or some other resilient or cushioning composition but the body 16 may be made of leather. The entire structure may be expeditiously manufactured and profitably sold at a reasonable price, and whenever the user wears the edge of the section 26 sufficiently to require adjustment of said section, he may readily remove it himself, turn it to another of its four positions when the boss is square, and refasten it in place. When this section has become so worn as to be of no further service, it may be thrown away and a new one purchased at small cost, and applied.

In the form of construction shown in Figs. 9 to 15, the body 16a is provided on its lower side with lugs 20a shaped and arranged differently from the lugs 20 above described, and if desired some or all of these lugs may be detachably mounted. The upper portion of the body 16a is formed with a rib 25a corresponding to the rib 25, and a rotatable heel section 26a is disposed against the lower side of said body, the relation of this section 26a with the rear end of the body 16a, being the same as that existing between the elements 16 and 26 above described. Moreover, the section 26a is secured in place both by a central screw 31a and by means of cement, but the entire area of the upper side of said section may be cemented to the body 16a. The section 26a is formed with a central upstanding boss 28a receivable in an opening 21a in the body 16a, and the lower side of said section 26a is formed with a socket 29a normally receiving a plug 35a which may be considered as identical with the plug 35. Both the body 16a and the rotatively adjustable section 26a are of concavo-convex form as shown in Figs. 13 and 15, before application of the improved heel to the leather heel, for tighter contact around the edges when drawn into flat form during attachment.

From the foregoing, taken in connection with the accompanying drawings, it will be seen that novel and advantageous provision has been made for carrying out the objects of the invention, and while preferences have been disclosed, attention is again invited to the possibility of making variations within the scope of the invention as claimed. For instance, it is not essential to provide the plug 35 or 35a with a pull cord, for it may be removed with the aid of any suitable instrument.

I claim:

40 A shoe heel comprising a body for attachment to a leather heel, a rotatively adjustable heel section contacting with the lower side of said body, and a screw extending centrally through said rotatively adjustable heel section for detachably mounting the latter, the upper side of said rotatively adjustable heel section having smooth radial areas to which cement will not adhere tenaciously, the remaining upper areas of said body in contact with said remaining upper areas being relatively rough to permit cement to readily adhere thereto, whereby if said rotatively adjustable heel section be cemented to said body, it will possess radial areas not cemented to said body, to facilitate insertion of a tool for prying off said heel section when desired.

BENJAMIN GILOWITZ.
